METHOD OF COMPLETING WELLS

Cicero C. Brown, Houston, Tex.

Application June 8, 1936, Serial No. 84,073

6 Claims. (Cl. 166—21)

My invention relates to a method of completing wells for production and has particular reference to the cementing and the steps taken to complete the well after the cementing operation has been performed.

It is an object of the invention to devise a method of cementing the well so as to entirely close off the entrance of any fluid whatever to the well bore and to then open up communication from the formation through the wall of the well to the interior thereof.

It is a further object to provide a means for cementing the well without the use of an unnecessary amount of cement. I contemplate forcing the cement around the lower end of the casing or liner without the necessity of filling the whole interior of the casing with cement in so doing.

It is a further object of the invention to prevent the mixing of the cement and the mud in the well and thus avoid impairing the efficiency of the cement.

I further desire to arrange the completing of the well so that there will be a minimum of danger of blowout in the finishing operations.

With reference to the drawings herewith, Fig. 1 is a central longitudinal section through a well casing showing a portion of the setting tool partly in elevation and partly in section.

Fig. 2 is a similar view showing the lower end of the casing or liner with the back pressure valve and setting sleeve in connection therewith.

Fig. 3 is a view partly in section and partly in elevation showing the setting tool connected with the setting sleeve at the lower end of the well in the desired position when the well is being cemented.

Fig. 4 is a side elevation of the liner and set shoe, certain parts being broken away for greater clearness.

Fig. 5 is an assembly view showing the apparatus employed, in position in the well.

I have illustrated my invention as adapted for use where a casing is set in the well and the well extended beyond the casing down to the producing formation and a liner is set from the casing down to the lower end of the well. This is a very common method of equipping the well, but I wish it to be understood that the invention is not confined to the use of a casing and liner, it being possible to set the liner all the way from the surface and where such construction is used the method of handling the well is the same.

With reference to Fig. 5, I have shown the well as equipped with a casing 1, which reinforces

the wall of the well down to the lower end of the casing. This casing has been cemented as shown at 2 so as to close off the entrance around the lower end of the casing of any fluid from above the same outside the casing. The well has then been drilled down through the casing making a hole of small diameter as shown at 3. In this smaller hole a liner is set. The hole has been drilled down through a producing formation which is indicated at 4, and the liner shown at 5 extends through the formation and has at its lower end a set shoe 6 of ordinary construction.

In lowering the liner through the casing to its position at the bottom of the well I employ the setting tool shown best in Fig. 1. A string of pipe 15 7, which may be a drill stem, is secured at its lower end to a collar 8. This collar is internally threaded at its lower end for connection at 9 to a nipple 10.

The nipple 10 extends beyond the collar a suitable distance and is threaded to receive a clamping collar 11. Above the threaded area the outer face of the nipple is provided with an annular shoulder 12, which is upwardly inclined to furnish a support for a plurality of latching dogs 25 13. Spaced above the shoulder 12 a collar 14 is screwed on the outer surface of the nipple and is held rigidly in position by a locking screw 15. The lower end of the collar 14 has an outer, downwardly extending flange 16 under which the 30 upper ends of the latching dogs may engage, as will be understood from the drawings.

On the outer surface of the collar 14 is an annular recess to receive a packing ring 17 of rubber or similar compressible packing material, the 35 upper end of which is grooved so as to be expanded by fluid pressure from above.

Between the collar 14 and the coupling 8 I provide an anti-friction bearing race including a lower ring 18, an upper ring 19, and an intermediate row of balls 20.

The latching dogs 13 have their lower ends extending downwardly below the shoulder and have outer downwardly inclined shoulders 21 to 45 be clamped between the upper tapered surface 22 of the clamping collar 11 and the interior of the setting collar with which it is to engage.

The setting collar is shown best in Fig. 2 but reference is made particularly to Fig. 3 in showing 50 the engagement between the setting tool and the setting sleeve. The setting collar has an upwardly extending barrel 23 and its lower end is inclined inwardly and reduced both in external and internal diameter. At its lower end it is extended 55

outwardly and threaded at 24 for engagement within the set shoe 6.

The upper end of the barrel 23 has a seat 26 upon which the lower ring 18 of the bearing race 5 may engage and be supported. Spaced below this upper end there is an interior shoulder 27 beveled to engage with the outer shoulders 21 upon the dogs 13.

Below the shoulder 21 and spaced therefrom 10 is an inwardly extending key or ridge 28 which is adapted to engage with outwardly extending key or ridge 29 upon the clamping collar 11.

The interior of the reduced lower end of the setting sleeve is formed with a packing member 15 30 having its lower end cleft to permit the entrance of pressure fluid to assist in sealing the same against the inner lower end of a nipple 10. Below the sealing ring 30 and within the cylindrical portion of the setting sleeve is an annular 20 recess 31 in which is housed a spring ring 32. Said ring is to be understood as a split ring similar to the ordinary metal piston ring. Its upper end is beveled inwardly so that when it is engaged by a plug such as shown at 33 it will be forced outwardly into the recess to allow the passage of the plug and then will move inwardly to engage within a latching recess 31 in the plug.

The lower end of the setting sleeve is formed 30 into a seat to receive the back pressure valve 34, which is of ordinary construction and need not be particularly described. It is held normally within the seat by a spring 35.

The set shoe 6 with which the lower end of the setting sleeve is engaged is connected to the lower 35 end of the liner and has a lower forwardly projecting blade 25 thereon to engage the formation and resist rotation of the liner. There is a central opening 36 through which fluids may pass downwardly past the back pressure valve.

The upper end of the liner may be equipped 40 with a packer as shown at 37 in Fig. 4, or the packer may be omitted as shown in Fig. 5. Where a packer is employed it may be set when the liner is in position to close the space between the lower end of the casing and the upper end of the liner.

When the packer such as is shown in Fig. 4 is employed the setting string has thereon a 45 packer setting device such as is shown at 44. This setting device has thereon dogs 45 which are adapted to be moved outwardly to engage with the upper shoulder 46 about the packer and thus allow the exertion of pressure upon the upper 50 end of the packer to compress it in the usual manner.

In assembling the setting tool within the liner preparatory for lowering the liner into position the setting tool will have the parts thereon in 60 position as shown in Fig. 1. The setting tool will be lowered into the setting sleeve arranged as shown in Fig. 2. When the setting tool has reached the seat in the setting sleeve it will be rotated to bring the laterally extending keys or lugs 29 on the clamping collar 11 into engagement with the key 28 on the interior of the setting sleeve. The setting tool will then be rotated in a lefthand direction so as to screw the clamping collar 11 upwardly beneath the lower 65 end of the dogs 13. This will move said lower end outwardly and will clamp the upper shoulders 21 on the dogs against the shoulder 27 on the setting sleeve. The setting tool will thus be locked in position rigidly against the sleeve as will be 70 understood from Fig. 3. It will be noted that

a seal is formed between the setting tool and the setting sleeve due to the upper packing ring 17 and the lower packing ring 30. There will be no escape of liquid around the connection between the setting tool and the sleeve, as will be clearly 5 understood. The anti-friction bearing at 20 is of use in the rotation of the setting tool in moving the clamping collar 11 into position such as has just been described. The lower ring 18 of the race-way will set frictionally against the upper end 10 of the setting sleeve and will be held stationary while the tool is being rotated. This furnishes a support which limits the downward movement 15 of the setting tool to the proper level and also allows more ready rotation of the setting tool while the clamping collar 11 is being moved into clamping position. With this rigid connection between the setting tool and the lower end of the liner the setting tool may be employed to lower the liner downwardly into position at the bottom 20 of the well. Mud may be pumped downwardly through the liner during the operation and when the bottom has been reached the circulation of the mud will serve to clear away the material at the lower end of the well so that the liner may 25 be properly seated.

When the parts are in this position I cement 30 through the setting string and around the lower end of the liner. In doing this I prefer to place a charge of cement of the proper amount into the upper end of the setting string and above the mud in the string. On the upper end of the charge of cement I place a plug such as is shown in Fig. 3 at 33. This plug forms a piston which is a separating barrier between the cement and the mud 35 which is pumped in above the plug. The pump pressure forces the cement ahead of the plug and downwardly around the lower end of the liner and upwardly outside thereof. I contemplate pumping a sufficient charge to displace all the 40 mud at the lower end of the well and force the cement upwardly the full length of the liner and around the lower end of the casing, as shown in Fig. 5. Where this is done the cement serves to pack off between the liner and the casing at the 45 upper end of the liner and to entirely seal against all liquids from the lower end of the well. When the plug 33 reaches the lower end of the setting tool it will be engaged by the ring 32 and will be held in position to close the lower end of the liner. 50

The setting tool may then be released and removed. This is done by rotating the setting string in the reverse direction to move the clamping ring 11 downwardly away from the dogs 13 so as to release the same and then the setting 55 tool may be drawn upwardly from the well.

The cement is allowed to set until it is hard and the next operation consists in perforating the liner at the level of the producing formation 4. There are many devices for perforating casing. I 60 contemplate using any preferred form of perforator preferably what is called a gun perforator, which forms openings as shown at 38 in Fig. 5, said openings extending radially outwardly from the liner and through the wall of cement adjacent thereto. 65 This allows the fluid from the producing formation to enter the well through the perforations.

The well is then ready to flow and if a strainer is desirable a strainer will be set. In some formations the use of a strainer will not be necessary. 70 In Fig. 5 I have shown a strainer 39, as having been connected at the lower end of a short string of pipe 40 and lowered into position with the set shoe 41 thereon seated at the upper end of the setting sleeve 23. At the upper end of the pipe 75

40 I have shown a canvas packer 42 which may be employed to close the space between the pipe 40 and the interior of the liner. This packer and its operation is well known in the art and forms 5 no part of the present invention and need not be further described. A flow tube 43 may then be lowered downwardly into the interior of the strainer and the well is ready for production.

It will be seen that with my present method 10 of completing the well it is possible to employ the cement most efficiently. Under other methods of cementing which are now common it is necessary to fill the whole interior of the liner with cement and force this large volume of cement downwardly through the large volume of mud which it displaces. In the present method only the cement 15 is circulated through a setting string of much smaller diameter and the smaller diameter of the setting string makes it possible to more effectively handle the cementing operation without waste. The mud which is below the cement is moved downwardly through the string and outwardly into the well and will be moved upwardly ahead 20 of the cement and will not mix with the cement 25 to such an extent as to impair the cementing operation as frequently occurs in the previous methods. I find that much more consistent and reliable results are obtained by this method.

Further, the cementing of the full length of 30 the liner up above the producing formation serves to effectively seal off the entrance of fluids into the well to mix with the production from the producing formation. When the liner and the wall of the cement has been perforated to 35 allow the entrance of production to the well, the well may be more easily controlled to prevent danger of blowout. The method is therefore more easily performed and is less wasteful of cement and more reliable in its results than other 40 methods now in common use.

What is claimed as new is:

1. A method of finishing a well for production including; cementing a casing in the well, drilling down through the cement and into a producing 45 formation, setting a liner in the well and simultaneously extending a fluid conducting line through said casing and liner to seal with the lower end of said liner, forcing cement through said liner and around the lower end of said liner 50 upwardly to cement the outer face of said liner and fill the space between said liner and casing, maintaining the interior of the liner free of cement, hardening said cement, perforating said liner and cement at the level of the producing 55 sand and setting a screen within said liner.

2. A method of finishing a well for production including; cementing a casing in the well, drilling down through the cement and into a producing formation, setting a liner in the well and 60 simultaneously extending a fluid conducting line

through said casing and liner to seal with the lower end of said liner, forcing cement through said line and around the lower end of said liner upwardly to cement the outer face of said liner and fill the space between said liner and casing, 5 withdrawing said line, hardening said cement, and perforating said liner and cement at the level of the producing sand so as to allow entrance of fluid therefrom to said liner.

3. A method of finishing a well for production, securing a fluid conducting pipe in sealing engagement with the lower end of a liner and lowering the liner to position in the well with said pipe, forcing cement through said pipe and upwardly outside the liner to a level above the 15 producing formation, discontinuing the cementing to prevent the entrance of cement to the interior of said liner, allowing said cement to set, detaching and removing said pipe, thus leaving the interior of said liner clear of cement, 20 puncturing said liner and said cement at the level of the producing formation and then setting screen in the liner.

4. A method of finishing a well for production, securing a fluid conducting pipe in sealing engagement with the lower end of a liner and lowering the liner to position in the well, forcing cement through said pipe and upwardly outside the liner to a level above the producing formation, closing the lower end of the liner above 25 the cement, maintaining the interior of said liner clear of cement, allowing said cement to set, removing said pipe, puncturing said liner and said cement at the level of the producing formation 30 and then setting screen in the liner. 35

5. A method of finishing a well for production, securing a fluid conducting pipe in sealing engagement with the lower end of a liner and lowering the liner to position in the well, preserving said sealing engagement while forcing cement 40 through said pipe and upwardly outside the liner to a level above the producing formation, maintaining the interior of said liner, clear of cement, allowing said cement to set, closing the lower end of said liner above any opening therein, removing said pipe, puncturing said liner and said cement at the level of the producing formation 45 and then inserting a flow line for the fluid from the well.

6. A method of finishing a well including connecting a setting string in sealing engagement with the lower end of the liner and setting a liner in the well, preserving said seal while forcing cement through said setting string around the lower end of said liner and cementing the 50 liner in position, plugging the lower end of the liner above any opening in the end thereof, and withdrawing the setting string. 55
